US0D1063052S

(12) **United States Design Patent** (10) Patent No.: **US D1,063,052 S**
(45) Date of Patent: ** Feb. 18, 2025

(54) **COOLING FIN**

(71) Applicant: **Delta Electronics, Inc.**, Taoyuan (TW)

(72) Inventors: **Chia-Hung Cheng**, Taoyuan (TW);
Ding-Wei Chiu, Taoyuan (TW);
Chih-Wei Yang, Taoyuan (TW)

(73) Assignee: **Delta Electronics, Inc.**, Taoyuan (TW)

(**) Term: **15 Years**

(21) Appl. No.: **29/823,523**

(22) Filed: **Jan. 18, 2022**

(51) LOC (15) Cl. **23-03**

(52) U.S. Cl.

USPC **D23/413**

(58) **Field of Classification Search**

(57) **CLAIM**

The ornamental design for a cooling fin as shown and described.

DESCRIPTION

FIG. 1 is a perspective view of a cooling fin showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 6 Drawing Sheets
